(57) **CLAIM**

The ornamental design for a bowl cap, as shown and described.

DESCRIPTION

FIG. 1 is an illustration of a top perspective view of the bowl cap.

FIG. 2 is an illustration of a side elevational view of the bowl cap.

FIG. 3 is an illustration of a top elevational view of the bowl cap.

FIG. 4 is an illustration of a bottom elevational view of the bowl cap.

FIG. 5 is an illustration of a bottom perspective view of the bowl cap; and,

FIG. 6 is an illustration of a top perspective view of the bowl cap within a bottle cap.

The broken lines showing a bottle cap are for the purpose of illustrating environmental structure and form no part of the claimed design.
